UNITED STATES PATENT OFFICE.

CHARLES DAY AND GEORGE EDWARD WINDELER, OF STOCKPORT, ENGLAND, ASSIGNEES TO GENERAL ELECTRIC COMPANY, A CORPORATION OF NEW YORK.

FUEL-PUMP.

1,115,180.

Specification of Letters Patent. Patented Oct. 27, 1914.

Original application filed June 13, 1912, Serial No. 703,395. Divided and this application filed July 21, 1913. Serial No. 780,106.

To all whom it may concern:

Be it known that we, CHARLES DAY and GEORGE E. WINDELER, subjects of the King of Great Britain, residing at Stockport, 5 county of Cheshire, England, have invented certain new and useful Improvements in Fuel-Pumps, of which the following is a specification.

The present application is a division of 10 our pending application, Serial No. 703,395, filed June 13, 1912, which division is made at the requirement of the United States Patent Office.

Our invention relates to pumps for supplying liquid fuel to high compression internal combustion engines and has for its 15 object to improve their construction and operation. Pumps of this class commonly supply fuel at a pressure greater than the 20 pressure pressure of the engine; this, for example, may require a pump to deliver fuel at a pressure of 500 to 800 lbs. per square inch or even higher. Such a pump to be satisfactory in service must be well made in 25 every particular.

The difficulties in making a single plunger pump, while many, are not so great as in making multiple plunger pumps. In the latter case great difficulty is experienced in boring the cylinders and drilling the cross-heads with the exact pitch distance between them and in so positioning the cylinder bores and cross-head holes when assembled that they are directly alined. In this connection 30 it is to be borne in mind that there can be no side clearance between the plungers and cylinder walls, the parts being fitted as snugly as possible. We solve the problem by so arranging the plungers that they are self 35 alined or self centered with respect to the cross-head.

Other features of our invention will be referred to later.

In the accompanying drawing which illustrates one of the embodiments of our invention, Figure 1 is a vertical section of a four-cylinder fuel pump, and Fig. 2 is a front elevation thereof.

6 indicates the main body of the pump 50 that is made of cast metal and is secured by bolts or other means to the engine frame 7. The lower part of the casing contains a supply chamber 8 which is filled with oil from a supply pipe 9 leading to a tank. Air is

admitted to the pipe and chamber by the 55 pipe 10. The bottom of the casing is provided with a removable cover 11 having an oil trough 12 to receive all leakage. This is carried off by a pipe 13. In the casing are as many cylinders 14 as are desired, usually one for each engine cylinder, said pump cylinders being equally spaced and occupying the same vertical plane. In some cases 60 it will be satisfactory to form the cylinders directly in the body itself, as for example, 65 when good dense castings can be obtained. A better arrangement, although somewhat more expensive, is to provide each cylinder with a separate liner 14a which can be hardened to reduce wear and later ground externally to exact size to fit the opening in the casting. This is a very advantageous arrangement if the body casting contains small blow holes or other imperfections. Without such a device the whole casting 70 would have to be discarded and these are expensive. Moreover it often happens that the imperfections are not in evidence until considerable work has been done on the casting. Whichever way the cylinder is made it 75 should be carefully reamed to exact size. 80

In each cylinder is a hardened and carefully ground plunger 15 that is snugly fitted in the cylinder or liner and is provided with small grooves 16 to reduce leakage. The 85 plunger passes through a stuffing box 17 of suitable construction, which also holds the liner in place by engaging the upper end thereof. The upper end of each plunger is provided with a cylindrical enlargement 18 90 which passes through the actuating cross-head 19. The upper end of the enlargement terminates in a head 20 having a flat underside which engages a finished surface on the upper side of the cross-head. The lower end 95 of the enlargement is threaded to receive the nut 21. Between the finished surface on the underside of the cross-head and the nut is a hardened and ground washer 22 to receive the downward thrust on the working stroke. 100 The washer and head 20 are closely and nicely fitted to the cross-head so that there is no lost motion in the vertical direction. After the parts are properly fitted the nuts are held against rotation by cotter pins. It 105 will be noted, however, that the enlargement 18 does not fill the hole in the cross-head, a small clearance being left all around it.

This is to permit of the plunger being guided by the cylinder wall instead of by the cross-head thereby compensating for faulty alinement or inaccuracies in machine work. Another way to look at it is that the cylinder determines the position of the plunger and also guides it while the cross-head serves solely as an actuator, moving the plunger into and out of the cylinder. At this point it is well to bear in mind that the cross-head also has to be guided in its movement and that its guides have to be machined and mounted on the frame 7. Of course the parts are machined as accurately as possible, and are also mounted as accurately as possible, still the opportunities for errors are great due to the very exact requirements, and, therefore, a limited amount of play between the plunger and the cross-head is of the utmost importance. All of the plungers are similarly constructed. In assembling they are slipped through the holes in the cross-head from above, after which the nuts 21 are mounted in place.

The cross-head may be of any suitable shape and size provided it is strong and can be well guided. It is provided with as many correspondingly spaced holes as there are plungers, the top and bottom surfaces co-operating on the plunger parts being carefully finished and exactly perpendicular to the axis of said holes. The back of the cross-head is enlarged as at 23 to form a good support and said support moves vertically in guides 24. This results in ample guiding surfaces with correspondingly low pressures thereon thus reducing wear. The cross-head is also provided with two flange pieces 25 through which the removable pin 26 extends, said pin connecting the lower end of the eccentric rod 27 and the cross-head for actuating the plungers. The pin is normally held in position by a pivoted latch 28 that enters a small groove 29 therein. By removing the pin 26, swinging the eccentric rod 27 out of the way and mounting the lever 30 in place as shown by dotted lines with its pin in the place of pin 26 the pump can be actuated by hand to fill the pipes leading to the fuel injectors or pulverizers in the engine and thus force out any air which may be contained in the system. After this the parts are replaced and the engine will be ready for operation. This hand pumping is only desirable or necessary after the engine has been shut down for a considerable period of time. The cross-head is driven by an eccentric 31 that is mounted on the end of the shaft 32, driven by the main engine shaft and may be the shaft which carries the cams for actuating the engine valves. Motion from the eccentric is transmitted to the cross-head by the rod 27 and the eccentric strap 33.

Each pump cylinder is provided with a

suction valve 35 and two discharge valves 36 and 37, the latter being arranged in series relation as regards the flow of fluid. 38 indicates the pipe that conveys the fuel to the engine injector or pulverizer. In the chamber 8 is located a horizontal shaft 39 upon which are mounted tappets 40 for controlling the seating of the suction valves. On one end of the shaft is an arm 41 that is connected by a rod 42 to the lever 43 which is vibrated in synchronism with the cross-head, said lever having a fulcrum 44 that is adjusted by the rod 45 of the governing mechanism to cause the suction valves to close earlier or later as the demand for fuel changes.

Certain of the novel and useful features illustrated and described in this application and not claimed herein form the subject matter of our aforesaid application, Serial No. 703,395, filed June 13, 1912.

In accordance with the provisions of the patent statutes, we have described the principle of operation of our invention together with the apparatus which we now consider to represent the best embodiment thereof; but we desire to have it understood that the apparatus shown is only illustrative, and that the invention can be carried out by other means.

What we claim as new and desire to secure by Letters Patent of the United States, is:—

1. The combination with a frame, of a body firmly secured thereto and containing a plurality of separately spaced pump cylinders, with their axes in the same plane and countersunk at their upper ends, a liner for each cylinder closely fitted therein, and all of said liners being finished to exactly the same size, a stuffing box in the countersunk upper end of each cylinder holding the liner in place, a plunger fitting each liner and passing through the stuffing box, a cylindrical enlargement at the upper end of each plunger having screwthreads at its lower end and terminating in a head having a flat under side, a nut engaging said screwthreads, a hardened and ground washer above said nut, a crosshead having a plurality of holes to receive said enlargements with a clearance all around them, the upper and lower surfaces of the crosshead being parallel and finished to afford a nice sliding fit for the terminal head and the washer respectively, guides on the frame for said crosshead, and means for reciprocating said crosshead.

2. The combination with a plurality of pump cylinders, of plungers therein, a cross-head engaging said plungers, two flange pieces on the crosshead, a removable pin passing through said flange pieces, a latch for holding said pin in place, a driving shaft operatively connected to said pin, and

a stationary fulcrum for a lever adjacent to said pin.

3. The combination with a plurality of pump cylinders, of a plunger for each cylinder having a cylindrical enlargement of greater diameter than the plunger or its shank, and a reciprocating crosshead having a plurality of cylindrical holes in line with said cylinders and enough larger than said enlargements to afford a good clearance all around them, whereby the plungers can be passed through the holes in the crosshead

to enter their cylinders, and the enlargements thereon will be received in said holes, and means for preventing axial play of said 15 enlargements in said holes without preventing lateral play therein.

In witness whereof, we have hereunto set our hands this first day of July, 1913.

CHARLES DAY.
GEORGE EDWARD WINDELER.
